(57) **CLAIM**

The ornamental design for a air mattress sleeping bag, as shown and described.

DESCRIPTION

FIG. 1 is a front elevational view of an air mattress sleeping bag showing my new design;

FIG. 2 is a rear elevational view thereof;

FIG. 3 is a side view, taken from the left side of FIG. 1;

FIG. 4 is a side view, taken from the right side of FIG. 1;

FIG. 5 is a top plan view thereof; and,

FIG. 6 is a bottom plan view thereof.

The diagonal perpendicularly crossed line shading seen in the FIG. 1 view indicates that the front panel portion of the air mattress sleeping bag is fabric.
